Primary Examiner — Paula Allen Greene(74) *Attorney, Agent, or Firm* — JD Patent and Trademark; Julian Forman(57) **CLAIM**

The ornamental design for a headset with biometric sensors, as shown and described.

DESCRIPTION

FIG. 1 is a bottom plan view of the headset with biometric sensors of the present invention.

FIG. 2 is a top plan view thereof.

FIG. 3 is a front elevation view thereof.

FIG. 4 is a front elevation bottom view thereof.

FIG. 5 is a back elevation view thereof.

FIG. 6 is a side elevation view thereof.

FIG. 7 is a front bottom plan view thereof; and,

FIG. 8 is a front right side elevation view thereof, the front left side elevation view being a mirror image thereof.

1 Claim, 8 Drawing Sheets(56)
